TAPE-DISPENSING MECHANISM

Alfred P. Krueger, Stratford, Conn., assignor to Derby Sealers, Incorporated, Derby, Conn., a corporation of Connecticut

Original application December 27, 1948, Serial No. 67,358. Divided and this application July 24, 1950, Serial No. 175,505

4 Claims. (Cl. 242—55.5)

1

This invention relates to a tape-serving machine and particularly to a machine for dispensing pressure-sensitive tape which is tacky or clingable upon one surface. The present application is a division of my co-pending application, Serial No. 67,358, filed December 27, 1948.

As illustrated the tape-dispensing mechanism is provided with means for supporting a supply of tape in the form of a roll from which the tape may be drawn by the operator who grasps the protruding end with his fingers and subjects it to a direct pull. The supply roll of tape is rotatably supported so that as the tape is drawn from the device it is permitted to rotate so as to unwind the tape thereon. A severing member is provided adjacent the forward or outlet end of the machine so that the operator may draw the tape against the severing member to tear off the desired strip. It will be understood, however, that the invention herein claimed is not limited to the specific features of the present device referred to above.

In drawing the tape from the supply roll where the latter is rotatably supported, there is often a tendency of the roll to overthrow after the tension on the tape has ceased, which overthrow sometimes interferes with the length of tape being dispensed and sometimes interferes with a subsequent operation of the device. It is, therefore, desirable in many instances to provide a certain amount of friction or drag for the roll holder upon which the supply roll is mounted so that there will be no tendency for the roll to rotate except when tension is applied thereto. Thus, any overthrow of the roll is prevented and the motion of the roll will stop immediately upon the cessation of tension upon the end of the tape.

There is also provided in the present structure a relatively light and portable dispenser for use with pressure-sensitive tape which is of simple construction so that it may be economically manufactured and at the same time is efficient in operation.

One object of the present invention is to provide a tape-dispensing machine in which the tape is drawn from the roll by a pull applied to the end of the tape and to provide means for placing a drag or brake upon the turning of the roll so as to prevent overthrow thereof.

Another object of the invention is to provide a machine for dispensing pressure-sensitive tape having a roll support upon which a supply roll of tape is mounted, the roll support being rotatably mounted in the machine but being subject to a certain amount of friction tending to resist rotation so as to prevent overthrow of the roll during the operation of the device.

To these and other ends the invention consists in the novel features and combinations of parts to be hereinafter described and claimed.

2

In the accompanying drawings:

Fig. 1 is a side elevational view of a tape-dispensing machine embodying my invention, the cover of the case being removed to expose the interior mechanism;

Fig. 2 is a front elevational view of the device; and

Fig. 3 is a sectional view through the axis of the roll holder taken on line 3—3 of Fig. 1.

10 To illustrate a preferred embodiment of my invention, I have shown a tape-dispensing mechanism comprising a base 10 upon which is supported a standard 11 to which the case 12 of the dispensing mechanism is rotatably secured. At its side adjacent the standard the case is provided with a boss 13 (Fig. 3) which threadedly receives a screw 14. This screw passes freely through an opening 15 in the upper portion of the standard 11, and its projecting end is secured to a nut 16. It will be obvious that rotation of the nut 16 will cause the standard 11 to be gripped between the nut and the boss 13 and thus hold the case 12 rigidly in place. When the screw 14 is loosened, the case may be rotatably adjusted about the screw with respect to the standard 11. Also, by unscrewing the screw 14 entirely from the boss 13, the case 12 is removed from the standard and may be held in the hand of the operator while being used.

30 Threadedly mounted in the forward portion of the boss 13 is a spindle or shaft 18 upon which is rotatably mounted the roll holder which supports the supply roll of tape. This roll holder comprises a hub 19 secured to a disk-shaped member 20, the latter having resilient arms 21 struck therefrom and projecting forwardly at substantially right angles to the disk 20 upon which the supply roll of tape 22 may be frictionally mounted, as shown for example in Fig. 1.

40 The forward end of the hub 19 is recessed as shown at 23 and a spring 24 is compressed between the bottom of this recess and a shoulder 25 formed integrally on the spindle 18. This spring, as will be apparent, exerts a frictional drag upon the hub 19 and, therefore, tends to hold the roll holder in any given position unless a positive effort is made to turn it. The amount of this friction or drag can be regulated by adjustment of the spindle 18 with respect to the boss 13.

50 The spindle 18 is reduced in size beyond the shoulder 25 as shown at 26 and then enlarged slightly as shown at 27, this end of the spindle projecting through an opening in a plate-like cover 28 which closes the front side of the case 12. A spring member 29 secured to the inner face of the cover is adapted to be engaged with the reduced portion 26 of the spindle so as to hold the cover releasably in place. It will be understood that the cover may readily be removed to permit access to the interior of the

mechanism for any desired purpose, such, for example, as to place a new roll of tape upon the roll holder.

The front of the case is provided with an opening 30, and, adjacent one end of this opening, a roller 31 is rotatably mounted in the case, with which roller the tacky side of the free end of the tape 32 is adapted to engage. It will be apparent that the operator by pulling on the free end of the tape will cause it to unwind from the supply roll 22 supported on the roll holder. The lower or tacky side of the tape will cling to the roller 31 so that the free end 32 will project from the case in position to be conveniently grasped by the operator so that it may be drawn from the machine.

A stripper member 34 is provided to engage the upper or non-tacky side of the tape and urge it downwardly against the roller 31, this stripper, as shown in Fig. 2, being in the form of a plate of substantially the same width as the roller 31, the end of the stripper adjacent the roller being curved slightly so that its sharp edge will not come in contact with the tape.

The stripper is secured to the forward end of a plate-like member 35 pivoted to the case at 36 so that it may swing rearwardly from the position shown in Fig. 1 about its pivot 36 and away from the roller 31 so as to permit the tape to contact the severing member to be hereinafter described. The plate member 35 is provided with an arcuate slot 37 within which is received a bolt or rivet 38 secured to the case so as to guide the movement of the stripper about its pivot 36.

A severing member is provided adjacent the end of the opening 30 which is remote from the roller 31 so that it normally stands within the case. This member is secured to a plate-like member 42 pivoted to the case at 43 so that it may swing forwardly about its pivot to project from the case for contact by the dispensed end of the tape.

The member 42 is provided with an arcuate slot 44 described about the pivot 43 as a center, which slot also receives the pin 38. A pin 45 is secured to the plate 42 which pin is disposed in a relatively large opening 46 in the plate-like member 35, thus linking the plates 35 and 42 together, but due to the fact that the opening 46 is considerably larger than the pin 45 relative movement of the two plates is permitted about their pivot so that when the stripper member 34 is raised by movement of the tape upwardly from the position shown in Fig. 1, the severing member will be moved forwardly so as to bring the tape into contact with it for the severing operation. A spring 47 secured at one end to the pin 45 and at the other end to the case normally holds the plate members 35 and 42 in the position shown in Fig. 1 of the drawings.

After the severing operation has been completed the stripper member by reason of the tension of the spring 47 will strip the unsevered end of the tape from the severing member and urge it downwardly toward and against the roller 31. The frictional drag exerted upon the roll holder by the spring 47 will prevent movement of the supply roll while the free unsevered end of the tape is being stripped from the severing member and moved into adhering contact with the roller 31 so as to insure that a suitable length of the free end of the tape will remain projecting

forwardly from the roller to be grasped by the operator. Otherwise, if the roll were free to rotate the end of the tape might be drawn rearwardly into the case.

While I have shown and described a preferred embodiment of my invention, it will be understood that it is not to be limited to all of the details shown, but is capable of modification and variation within the spirit of the invention and within the scope of the claims.

What I claim is:

1. A mechanism for dispensing pressure-sensitive tape comprising a supporting frame, a spindle fixed to said frame, a roll holder rotatably mounted on said spindle, said holder having a hub rotatably mounted on said spindle, a shoulder on said spindle, a spring acting between said shoulder and said hub to place a frictional drag on the holder, said hub being recessed to receive

20 a part of said spring, and means for securing the spindle to the frame for adjustment in an axial direction to adjust the tension of the spring.

2. A mechanism for dispensing pressure-sensitive tape comprising a supporting frame, a spindle fixed to said frame, a roll holder rotatably mounted on said spindle, said holder having a hub rotatably mounted on said spindle, a shoulder on said spindle, a spring acting between said shoulder and said hub to place a frictional drag on the holder, and means for adjusting the tension of said spring, said means comprising a threaded connection between the spindle and the frame to permit axial adjustment of the spindle.

3. A machine for dispensing pressure-sensitive tape comprising a frame, a roll holder rotatably mounted on the frame for supporting a roll of tape, an element mounted on the frame to which the free end of the tape adheres, a severing member spaced from said element against which a length of tape may be torn off, a stripper for stripping the unsevered end of the tape from the severing member and moving it against said element, and means for resisting rotation of the roll holder to prevent movement thereof while the unsevered end of the tape is so moved.

4. A machine for dispensing pressure-sensitive tape comprising a frame, a roll holder rotatably mounted on the frame for supporting a roll of tape, an element mounted on the frame to which the free end of the tape adheres, a severing member spaced from said element against which a length of tape may be torn off, a stripper for stripping the unsevered end of the tape from the severing member and moving it against said element, and means for resisting rotation of the roll holder to prevent movement thereof while the unsevered end of the tape is so moved, said means comprising a frictional drag on a part of said holder.

ALFRED P. KRUEGER.
